We claim, the ornamental design for a contactless data carrier, as shown and described.

DESCRIPTION

The contactless data carrier is used to conduct wireless communication.

FIG. 1 is a top plan view;

FIG. 2 is a bottom plan view;

FIG. 3 is the front elevational view;

FIG. 4 is the rear elevational view;

FIG. 5 is a right side elevational view;

FIG. 6 is a left side elevational view;

FIG. 7 is a perspective view showing a top side, a front side, and a right side thereof; and,

FIG. 8 is a perspective view showing a bottom side, a rear side, and a left side thereof.

The broken lines in the figures depict portions of the contactless data carrier that form no part of the claimed design.
